(57) **CLAIM**

The ornamental design for a tray and lid set for syringes and medications, as shown and described.

DESCRIPTION

FIG. 1 is an exploded perspective view of a tray and lid set for syringes and medications showing our new design.

FIG. 2 is a perspective view of the tray element of the tray and lid set for syringes and medications shown separately for clarity of illustration.

FIG. 3 is a front view thereof.

FIG. 4 is a back view thereof.

FIG. 5 is a top view thereof.

FIG. 6 is a bottom view thereof.

FIG. 7 is a left side view thereof.

FIG. 8 is a right side view thereof.

FIG. 9 is a perspective view of the lid element of the tray and lid set for syringes and medications shown separately for clarity of illustration.

FIG. 11 is a back view thereof.

FIG. 12 is a top view thereof.

FIG. 13 is a bottom view thereof.

FIG. 14 is a left side view thereof; and,

FIG. 15 is a right side view thereof.
